William A. Greene of Troy, N. Y.

DES. 2433

Letters Patent No. 2433. Dated Sept. 25, 1866.

Design for a Blacking Brush Handle.

The Schedule referred to in these Letters Patent and making a part of the same.

To all whom it may concern:

Be it known that I, William A. Greene of Troy in the County of Rensselaer and State of New York have invented or produced a new and original Design or form of Blacking Brush Handle, of which the following is a full and exact description of the same being had to the accompanying drawing and to the letters of reference marked thereon making part of this Specification.

The description is as follows, to wit: The annexed drawing represents a blacking brush with a box of blacking on and in the handle of the brush. Said handle being made of metal and the brush secured to it.

To give said new and useful form to this handle it is extended back from the brush in a loop like form A, B, C, in manner as shown and the central part D, of said handle is recessed or formed so as to receive and hold a box of blacking in manner as shown, and the top, or top part E, of said handle which holds the blacking part of said brush is made in a slanting form or is inclined toward the polishing part of the brush.

Having fully described my new form of Blacking Brush Handle. What I claim as my invention and desire to secure by Letters Patent is,

The Design or form of handle for blacking brushes as herein set forth and shown in annexed drawings.

Witness,

J. S. Barry.

J. J. Savage.

Wm A. Greene
